UNITED STATES PATENT OFFICE.

S. WHITE PAINE, OF ROCHESTER, NEW YORK.

CHECK, DRAFT, OR RECEIPT BOOK.

SPECIFICATION forming part of Letters Patent No. 352,776, dated November 16, 1886.

Application filed September 18, 1885. Serial No. 177,472. (Model.)

To all whom it may concern:

Be it known that I, SETH WHITE PAINE, a citizen of the United States, residing at Rochester, in the county of Monroe and State of New York, have invented new and useful Improvements in Check, Draft, and Receipt Books, of which the following is a specification.

This invention relates to a check, draft, or receipt book having a permanently-attached leaf-cutter, by which a check, draft, or receipt can be quickly and neatly detached from its stub or coupon, leaving the latter in the book.

My invention consists in the combination, with a book for checks, drafts, receipts, &c., of a transverse cutter or straight-edge having at each end a spring-arm riveted to the book-cover; also, in the combination, with a check, draft, or receipt book having leaves and covers 20 of equal width, said leaves being recessed or cut away on each top and bottom edge near their attachment to the covers, of a transverse cutter having arms permanently attached to the back cover of the book and lying in the recesses formed in the edges of the leaves, whereby said cutter-arms are flush with the uncut edges of the book.

In the annexed drawings, Figure 1 is a perspective view of my improved check, draft, or receipt book with cutter attached, each leaf of the book being adapted to one check, draft, or receipt. Fig. 2 is a similar view showing a book with longitudinally-divided leaves for several checks, drafts, or receipts. Fig. 3 is a detail view of a cutter or straight-edge with spring-arms adapted to be riveted to the book-cover. Figs. 4 and 5 are detail views of cutters designed to be pivoted to the book-cover.

Referring to the drawings, the numeral 1 designates the book-covers, and 2 the leaves. These covers and leaves I prefer to cut away or recess at 3 on the top and bottom edges of the stub portion. To the back cover of the book is permanently attached a cutter, 4, having a sharpened straight-edge, 5, that extends transversely across the leaves of the book at the line of demarkation between the body of the check, draft, or receipt and its coupon or stub portion. This cutter may have spring-arms 6, that are riveted to the back cover, as shown in Fig. 2; or the arms of the cutter may

be formed with pivots 7, as shown in Fig. 4, and these pivots, as shown in Fig. 5, may be made of such length as to meet at or about the center. The cutters and their arms may be 55 made of brass, steel, or other suitable material. The straight-edged cutter with spring-arms is adapted to bear firmly on the leaves of the book, and is always in position for use as a guide and cutter in detaching a check, 60 draft, or receipt.

The pivoted cutter, when turned down with its straight cutting-edge between the check and stub, can be used as a guide and cutter for detaching the check, and it has also an 65 inner straight cutting-edge that may be used for disconnecting the stub from the book when said pivoted cutter is turned back.

It will be observed that the book-covers and leaves are of equal width and are cut away or 70 recessed at the top and bottom edges of the stub portion. By making the leaves and covers in this way I effect a considerable saving in the cost of manufacture, and the recesses 3 in the top and bottom edges serve to receive the 75 attaching-arms of the cutter, so they will be flush with the uncut edges of the book, thus economizing space in packing and avoiding projection of the cutter-arms beyond the book.

In the manufacture of books with two or 80 more checks, drafts, or receipts on each leaf, I form the leaves with longitudinal slits 8 between the several checks, drafts, receipts, or other printed forms, and these slits 8 may, if desired, be extended between the stubs. By 85 this means I dispense with the use of a ruler for separating the checks lengthwise, and I also avoid the expense of providing the transverse cutter with a right-angled arm, as sometimes hitherto employed for this purpose. It 90 is obvious that the cost of slitting the leaves of the book at the time of manufacture is much less than would be required to provide the transverse cutter with a horizontal cutting-arm for use in dividing the checks longitudinally, especially as such horizontal arm must 95 be made accurately adjustable in order to be effective.

With the longitudinally-slitted leaves I use a straight-edge, 4, that is connected to the 100 back of the book by means of spring-arms 6, whereby the straight-edge is at all times held

firmly across the longitudinal slits 8 in such a way as to prevent accidental tearing of the stubs.

What I claim is—

- 5 1. The combination, with a check, draft, or receipt book, of a transverse cutter having spring-arms fastened to the back of said book, substantially as described.
2. The combination, with a check, draft, or receipt book having the top and bottom edges of its stub portion recessed, of a transverse

cutter attached to the back cover of the book, with its cutting-edge across the leaves and its attaching-arms lying in the recessed edges of the book, substantially as described.

15

In testimony whereof I affix my signature in presence of two witnesses.

S. WHITE PAIN.
